GUIDING ARRANGEMENT FOR A DOCUMENT REPRODUCING MACHINE

Carter J. Hughey, Rochester, N. Y., assignor to
 Eastman Kodak Company, Rochester, N. Y., a
 corporation of New York

Application February 3, 1934, Serial No. 709,669

7 Claims. (Cl. 271—71)

The present invention relates to a guide means for properly discharging checks or similar documents from a photographic recording machine and more particularly to the provision of a pair 5 of guide members which conduct the documents during discharge from the machine into a receiving hopper.

There is a general tendency for checks and other documents of similar dimensions to become 10 curved with the edges bent toward the face of the document. This curvature is also increased by the general practice of placing rubber bands around a stack of checks. If the checks are so stacked for any appreciable length of time, the 15 curvature is increased and becomes more permanent. Such curvature is not removed from the checks even by passage over a drum which bends the checks to curve in the opposite direction. As a result, when the checks are discharged 20 from a reproducing machine, they exhibit a tendency to turn over during the drop from the document exit to the receiving hopper. The reversal of a check or change in order of the checks is very objectionable and confusing to the operators who must perform subsequent calculations 25 with them.

The primary object of the present invention is the provision in a document recording or reproducing machine of a pair of guide members which 30 flex the check during discharge from the machine in such a manner that each subsequent check is properly conducted without inversion to the receiving hopper or pile of checks.

Another object of the invention is the provision 35 of a pair of guide members for guiding a check during discharge from a document handling machine, one guide member being fixed and including a curved or spirally curved edge and the other guide member including a finger which 40 is resiliently pressed against the periphery of a feeding drum to direct the checks against the curved edge of the fixed guide member.

A further object of the invention is the provision 45 in a document handling machine of a fixed guide member having a curved edge and a movable guide member having a finger for directing checks against the curved edge of the fixed guide member, said guide members being displaced in a direction along the surface of a feeding drum 50 so that one end of the check is directed sharply down into the receiving hopper.

Still another object of the invention is the provision 55 in a document handling machine of a fixed guide member having a curved edge and a movable guide member including a finger which is

resiliently pressed against the feeding drum, which is normally spaced from the feeding drum but which may be moved by a manually operated control means resiliently to press against the periphery of the drum and press documents 5 against the surface of the drum and along the curved edge of the fixed guide member.

Other and further objects of the invention will be suggested to those skilled in the art as the description of the invention proceeds hereinafter. 10

The above and other objects of the invention are embodied in the arrangement of a pair of guide members adjacent the exit of a feeding means including a feeding drum, one of said guide members being fixed and provided with a curved 15 or spirally curved edge and the other of said guide members including a finger which is resiliently pressed against the periphery of the feeding drum and which directs documents against the curved edge of the fixed guide member. 20 A manually operated control means may be associated with the movable guide member for rendering the same operative or inoperative at will.

Reference is hereby made to the accompanying 25 drawings wherein like reference characters designate similar elements and wherein:

Fig. 1 is a vertical, longitudinal section through a document handling machine which is equipped 30 with a pair of guide members according to the present invention.

Fig. 2 is a fragmentary vertical section through a document handling machine similar to Fig. 1 but showing the movable guide member in inoperative position. 35

Fig. 3 is a side elevation of the feeding drum and guide members as viewed from the left side of Fig. 1.

In the illustrated embodiment of the invention, the document handling machine is enclosed 40 within a housing 10 which is provided with a main feeding hopper 11. A feeding board 12 extends horizontally from the housing 10 while a vertical wall 13 is provided in the housing adjacent the feeding board 12. An opening 14, see Fig. 45 2, is provided at the juncture of feeding board 12 and vertical wall 13. A guideway 15 is located to conduct documents from the feeding board 12 to a feeding means which will be later described in detail. A recess 16 is located between the feeding board 12 and guideway 15. 50

The feeding means of the document handling machine is of recognized design and includes a feeding drum 17 which is rotatably mounted upon a shaft 18 and which is provided with a 55

plurality of circumferential grooves 19. A plurality of wires 20 are attached at one end to a rod 21 and at the other end to a rod 22. The wires 20 make contact with a portion of the periphery of feeding drum 17 and function to hold the documents evenly against the surface of feeding drum 17.

A check straightening device is provided at the entrance to the feeding means composed of 10 the feeding drum 17 and plurality of wires 20 and may consist of a roller 23 mounted on a shaft 24. A document control member for operating the camera drive, not shown, includes a plate 25 which has a plurality of lugs 26 adapted to extend into the grooves 19 of drum 17 and which is rotatably mounted upon a shaft 27.

An auxiliary feeding hopper includes the opening 14 between feeding board 12 and vertical wall 13 and the guideway 15 which is inclined 20 from the feeding board 12 to a point adjacent the feeding drum 17.

A cover member is movably mounted on the housing 10 of the machine and is adapted in closed position to cover the opening 14, but in 25 open position permits the introduction of comparatively long documents, such as letters, into the opening 14 and along the guideway 15 to the periphery of feeding drum 17. The cover member is composed of a cover 28 which has a side plate 29 attached thereto. The side plate 29 is 30 rotatably mounted on the housing 10 by means of a pivot 30 and carries a projection or abutment 31, preferably turned out of the stock of side plate 29.

35 The cover 28 is angular in formation and has a portion 32 which is adapted in closed position of the cover member to fit into recess 16 and lie flush with the horizontal surface of feeding board 12. The cover member has another portion 33 40 which is preferably at right angles to the portion 32 and which is adapted in closed position of the cover to lie flush with the vertical wall 13 of the housing 10. In other words the cover member is so constructed that in closed position 45 said cover member closes the opening 14 and has portions which are flush with the horizontal surface of the feeding board 12 and the vertical surface of the wall 13, but which in open position permits access to the opening 14, guideway 15, 50 and feeding drum 17.

A holding means for the cover member may 55 comprise a leaf spring 56 which is fastened to the housing 10. The free end of spring 56 will engage the rear edge of side plate 29 resiliently to maintain the cover member in closed position as shown in Fig. 1 and will engage the diagonal edge 29' of side plate 29 resiliently to hold the cover member in open position as shown in Fig. 2.

60 A guide member 34 is connected to the cover member and is adapted in open position of the cover member to lie upon the periphery of drum 17 and in closed position of the cover member to be spaced from the periphery of drum 17. The guide member 34 is pivotally mounted on a rod 65 35 which extends from side plate 29 and has an arcuate portion 34' which is concentric with the drum 17 and which extends lengthwise of the drum.

70 When the cover member is in open position, as shown in Fig. 2, the arcuate portion 34' of the guide member 34 lies or rests upon the periphery of drum 17 so that long documents, such as letters, are evenly held against the surface of the drum while being fed over the feeding board 75 12 and guideway 15. When the cover member is

moved to closed position with its portions 32 and 33 flush with feeding board 12 and vertical wall 13, respectively, the abutment 31 on side plate 29 engages the gate member 34 and swings the same away from the periphery of drum 17. This position of the guide member 34 is illustrated in Fig. 1.

The feeding means of the machine discharges the documents into a receiving hopper 36. The receiving hopper 36 is adjustable to vary its size 10 and its elevation. The hopper 36 is pivotally connected to the machine by a link 37 and has an inclined bottom 38 which has a plurality of dependent teeth 39. The front wall 40 of the housing 10 is provided with a plurality of slots 41. It 15 is evident that the distance between the front wall 40 of the housing and the front wall of the hopper 36 may be varied by moving the inclined bottom 38 so that other teeth 39 engage the edges of the slot 41 and front wall 40. Furthermore, 20 the elevation of hopper 36 may be varied by swinging said hopper 36 so that the inclined bottom 38 is removed from one of the slots 41 and re-inserted into a higher or lower slot 41.

The wires 20 extend tangentially from the surface of drum 17 to the rod 22 and form an exit 25 for the feeding means. If the documents have a curvature similar to that existing in the check 42 in the main feeding hopper 11, there will be a tendency for the checks to be inverted during passage from the exit of the feeding means to the bottom of the hopper. In other words, curved checks as discharged from the feeding means exit 30 may turn over during their fall to the bottom of the hopper and come to rest with the face of 35 the checks upward. If this inversion of the check was regular, it would not be so objectionable, but would still be undesirable since the checks would be piled in reverse order from that in which they entered the machine. The difficulty overcome by 40 the guide means of the invention has now been stated.

The guide means of the invention accomplish the movement of checks from the exit of the feeding means to the receiving hopper 36 in 45 proper position and in proper order. Such guide means are composed of a fixed guide member and a movable guide member.

The fixed guide member 43 is located adjacent the exit of the feeding means and is preferably 50 fastened along its upper edge to the lower portion of the feeding board 12. The fixed guide member 43 has a fin-like shape and has a curved lower edge which extends from the surface of drum 17 toward the interior of receiving hopper 36. 55 Guide member 43 includes a pointed portion 44 which is bent out of the plane thereof and has a finger 45 which extends into the peripheral grooves 19 of the drum 17. The aforementioned 60 curved edge of the fixed guide member 43 extends from the periphery of drum 17 at first tangentially along the lower edge of finger 45 and then is curved downwardly away from drum 17 and along the lower edge of pointed portion 44. 65 Owing to the fact that pointed portion 44 is bent out of the plane of guide member 43, it may be correctly stated that the curved edge is spirally curved.

The remainder of the guide means is composed 70 of a movable guide member. Such a movable guide member is constituted principally by a finger 46 which is resiliently pressed against the periphery of drum 17. The finger 46 is pivotally mounted on a cross-rod 47 and a coil spring 48 75 encircles rod 47 with one end 48' extending along 75

finger 46 and with the other end 48" extending downwardly.

A control means for the movable guide member includes a shaft 49 which is rotatably mounted within housing 10. An arm 50 is fastened to shaft 49 and is adapted to engage the end 48" of coil spring 48 to move the finger 46 against the surface of drum 17, arm 50 being provided with a notch 50' which engages the spring end 48". A crank 10 51 is also fastened to shaft 49 and is connected by a pivot 52 to an operating lever 53 which extends to the exterior of the machine. The operating lever 53 is provided with a U-shaped slot 54 which is adapted to engage a pin 55 on the 15 housing 10.

The movable guide member is normally in inoperative position which is illustrated in Fig. 2. The movable guide member serves no useful purpose in conducting long letters through the feeding means and consequently is used alternatively and not simultaneously with the auxiliary feeding hopper adjacent the feeding board 12. When it is desired to run checks, and especially checks with an appreciable curvature, through the feeding means of the machine, then the operating lever 53 is raised, pressed inwardly, and then pressed downwardly, so that the other leg of U-shaped slot 54 now engages the pin 55 according to the illustration of Fig. 1. At the same 20 time the crank 51 and arm 50 are rotated in a clockwise direction. The arm 50 bends the end 48" of coil spring 48 to swing the resilient finger 46 against the periphery of drum 17. It should be noted that the finger 46 is resilient in itself 25 and is resiliently held against the periphery of drum 17 by the coil spring 48. The movable guide member is now in operative position and directs the check to the curved edge of the fixed guide member 43 for proper deposit of the checks in 30 the hopper 36.

Referring to Fig. 3, it will be noted that the finger 46 is displaced from the finger 45 and major portion of guide member 43 in a direction along or axially of the drum 17. Furthermore, 45 the curvature of pointed portion 44 in bending out of the plane of fixed guide member 43 is in a direction toward the finger 46.

The two guide members of the invention unquestionably function to conduct the checks into 50 the receiving hopper 36 without permitting a change in order or inversion of any check. It cannot definitely be stated, however, whether this proper deposition of the checks is the result of reverse bending to remove the arcuate state 55 of the checks and caused by guiding the checks along the curved edge, or whether it is the result of causing one end of the check to droop sharply and lay against the stack of checks before the entire check has left the finger of the movable 60 guide member. It may be that these effects function simultaneously in the proper discharge of the checks to the hopper.

The course and curvature of the checks in their movement from the exit of the feeding means 65 to the receiving hopper will now be described. As the check moves through the exit of the feeding means and away from the wires 20, the resilient finger 46 continues to hold at least a portion of the check against the periphery of drum 70 17. The finger 46 tends to direct the check farther around the periphery of drum 17, but the finger 46, which extends into peripheral grooves 19, causes the check to be moved along its lower edge and, in fact, to move in a path tangential to the periphery of drum 17. The curved edge of 75

guide member 43 will turn the front edge of the check downwardly. One end of the check, see Fig. 3, will droop quite sharply, both as a result of the curved edge of the fixed guide member 43 and as a result of the fact that this end of the check is not supported. The curvature of pointed portion 44 in a direction toward the resilient finger 46 will cause this sagging end of the check to be bent downwardly more sharply as the check is ejected from the exit of the feeding means. 10 The most desirable results are obtained when the lower end of the check rests upon the check pile before the rear edge of a check has moved past the end of finger 46. Under this condition, with one end of the check resting across the pile of 15 checks below, the check merely falls into place without turning.

Many modifications or colorable imitations of the invention will be obvious to those skilled in the art and the present disclosure is to be construed in an illustrative and not in a limited sense. The scope of the invention is defined by the following claims.

Having now particularly described my invention what I desire to secure by Letters Patent of 25 the United States and what I claim is:

1. In a machine for handling documents, the combination with a feeding means having an exit and including a drum for moving documents, of a fixed guide member located adjacent to the 30 exit of said feeding means and having a curved edge which extends spirally from said drum, and a movable guide member adapted resiliently to press against the periphery of said drum and for directing a document, which is leaving said feeding means, into contact with said curved edge of the fixed guide member, said guide members being displaced along said drum with the spirally curved edge of said fixed guide member being variably displaced from said movable guide member. 40

2. In a machine for handling documents, the combination with a feeding means having an exit and including a drum for moving documents, of a fixed guide member located adjacent to the 45 exit of said feeding means and having a curved edge to form a pointed portion which is bent out of the plane of the fixed guide member, and a resilient guide member adapted resiliently to press against the periphery of said drum and for directing a document, which is leaving said feeding means, into contact with said curved edge of the fixed guide member, the curved edge of said pointed portion being differentially displaced with respect to said resilient guide member and in an axial direction of said drum. 55

3. In a machine for handling documents, the combination with a feeding means having an exit and including a drum for moving documents, of a fixed guide member located adjacent to the 60 exit of said feeding means and having a curved edge to form a pointed portion which is bent out of the plane of said fixed guide member, and a resilient guide member adapted resiliently to press against the periphery of said drum and for directing a document, which is leaving said feeding means, into contact with said curved edge of the fixed guide member, said guide members being variably displaced along said drum and said pointed portion of the fixed guide member being bent toward said resilient guide member. 70

4. In a machine for handling documents, the combination with a feeding means having an exit and including a drum for moving documents and which is provided with a plurality of circumferential grooves, of a fixed guide member hav- 75

- ing a stationary finger which extends into one of said circumferential grooves and having a curved edge which extends spirally from the periphery of said drum, and a movable guide member
- 5 5. adapted resiliently to press against the periphery of said drum and for directing a document which is leaving said feeding means into contact with the curved edge of said stationary guide member.
- 10 5. In a machine for handling documents, the combination with a feeding means having an exit and including a feeding drum for moving documents, of a resilient finger pivotally mounted in spaced relation to said drum and movable into contact therewith for holding a document against
- 15 15. the periphery of the drum beyond said exit, and a control means including an arm for moving said finger and including an operating lever which extends to the exterior of the machine for manual operation of the control means.
- 20 6. In a machine for handling documents, the combination with a feeding means having an exit and including a feeding drum for moving

documents, of a finger pivotally mounted in spaced relation to said drum, a control means including an arm for moving said finger and including an operating lever, and a resilient means between said arm and said finger for resiliently 5 pressing said finger against the periphery of said drum beyond the exit of said feeding means.

7. In a machine for handling documents, the combination with a feeding means having an exit and including a feeding drum for moving 10 documents, of a resilient finger pivotally mounted in spaced relation to said drum and movable into contact therewith for holding a document against the periphery of the drum beyond said exit, a control means including an arm for mov- 15 ing said finger and including an operating lever extending to the exterior of the machine, and a coil spring with one end engaging said arm and the other end engaging said finger for resiliently pressing said finger against the periphery of said 20 drum beyond said exit.

CARTER J. HUGHEY.
